UNITED STATES PATENT OFFICE.

WESLEY W. GARY, OF BOSTON, MASSACHUSETTS.

ELECTRICAL SIGNAL.

SPECIFICATION forming part of Letters Patent No. 240,693, dated April 26, 1881.

Application filed July 29, 1880. (Model.)

To all whom it may concern:

Be it known that I, WESLEY W. GARY, of Boston, in the county of Suffolk and State of Massachusetts, have invented certain Improvements in Electric Signals, of which the following is a specification.

My invention relates to that class of electric signals in which a permanent and an electro-magnet are employed, and the signal-bearing arm or device thrown into action by a reversal of the electric current.

The invention consists in so constructing and arranging the parts of the apparatus that the moving signal-bearing portion thereof shall be held out of action by the combined forces of gravity and magnetic attraction.

In the accompanying drawings I have represented a signaling-instrument especially intended for use in flagmen's stations, the same consisting of an upright swinging arm or lever carrying at its upper end an electro-magnet, the core of which serves as an armature for the permanent magnet, said arm carrying also a spring-arm provided with a bell, which is caused to ring when the swinging arm falls away from the permanent magnet. The positions of the permanent and electro magnets may obviously be reversed without modifying the principle of operation.

Figure 1 represents a perspective view of my improved device; and Figs. 2 and 3, respectively, side elevations of the same, with the swinging arm in its two positions.

In practice I prefer to mount the several parts of the apparatus upon a bracket or support consisting of a vertical and a horizontal portion, as shown in the drawings, in which—

A represents the bracket or support, and B a permanent magnet secured rigidly to the upright face of the same, while C represents a swinging arm turning or swinging upon an axle or spindle, *a*, at its lower end, the ends of the spindle being sustained in suitable bearings, as shown. At its upper or free end the arm C is furnished with an electro-magnet, D, the core of which, *b*, is extended outward beyond the ends of the wire-spool and flattened, as shown, forming an armature for the permanent magnet B. The core or armature is of soft iron, and is placed in such position upon the swinging arm C that when the latter is in

an upright position its flattened ends shall bear against or stand close to the face of the permanent magnet B, near or at the ends, and against opposite poles of the same, and the 55 spindle *a* is so located that the center of gravity of the arm and electro-magnet shall fall in line therewith, or, as is preferred, slightly inside thereof, on the side toward magnet B.

By this arrangement of the parts, it will be 60 seen the arm C, with its electro-magnet and signal device, will be held naturally in its upright position when once so placed; but it will likewise be seen that unless otherwise retained in such position the jar and vibration 65 occasioned by passing trains would soon throw the arm past the center of gravity and permit it to fall. The force necessary to retain the arm in its upright position against the jar and vibration I secure by the use of the permanent 70 magnet B, its attractive force holding the core or armature *b* firmly to its face so long as said armature remains depolarized.

The swinging arm C is furnished with an elastic or spring arm, E, carrying at its outer 75 end a bell, F, and is limited in its outward movement by a stop or support, G, as shown. When the arm with its bell falls down it is suddenly stopped by the support G, and the bell is caused to ring. To insure the release 80 of the arm and the ringing of the bell at the proper times it is only necessary to produce in the core or armature *b* a polarity the same as that of the permanent magnet, whereupon, like poles repelling, the armature will be thrown 85 outward and the arm caused to fall back. This polarization is effected by passing an electric current from a generator or battery of any kind through the helix of the electro-magnet, for which purpose the wires *cd* of the helix are 90 carried down to the bed of the instrument and connected, by binding-screws or otherwise, with the wires of the generator or battery, as shown.

In the drawings I have shown the arm and electro-magnet arranged to fall away from the 95 magnet B to a considerable distance, in order that in the event of an alternating current being employed to actuate the device the action shall be the same as with a continuous current, the armature being thrown so far outward by the first repelling impulse that it is no longer subject to the influence of the per-

manent magnet. This arrangement is particularly advantageous, for the reason that the position of the arm as well as the ringing of the bell affords a means of ascertaining whether 5 or not the device has been operated, so that in the event of the attendant being away when the signal is given his attention will be called to the fact on his return.

It is apparent that the arm may be suspended, 10 if preferred, the action remaining the same.

By the use of the permanent magnet and the arrangement of parts shown, I am enabled to dispense with all latches, detents, and fastening devices, which at once add to the expense 15 and to the difficulty of operation, and the signal is held out of action without the expenditure of any electric current.

After operation the signal-bearing arm is returned to its upright position by hand, the 20 core or armature being again depolarized.

It is preferred that there shall not be a perfect contact of the armature with the permanent magnet, as when a very slight space is left between them the repelling action is quicker 25 and more certain in throwing out the arm.

I am aware that it is not broadly new to retain a signal in one position by the attractive force of a permanent magnet, and to cause its release from such position by reversing the 30 polarity of the armature relatively to the permanent magnet; hence I make no claim thereto, broadly considered. I am not, however, aware that any one has ever before either balanced the signal-arm or arranged the parts in such 35 manner that the force of gravity should act in conjunction with the attractive force of the permanent magnet, to retain the signal out of action. By my construction and arrangement I am enabled to control much larger and heavier

signals than can otherwise be done with a given 40 magnet-power and electric current.

Having thus described my invention, what I claim is—

1. In a signal-instrument adapted to be operated by an electric current, the combination 45 of a swinging signal-bearing arm pivoted and supported at its lower end, an electro-magnet, and a permanent magnet, said magnets being attached, one to the swinging arm and the other to a fixed support, and arranged to operate 50 substantially in the manner set forth, whereby the permanent magnet is caused to retain the signal-bearing arm in an upright position without having to sustain the weight thereof until the passage of an electric current through the electro-magnet, and thereupon to release the 55 same.

2. In a signaling-instrument, the combination 60 of an upright swinging signal-bearing arm, having its pivot located outside of the center of gravity, and a permanent magnet and an armature secured, respectively, to a fixed support and to the swinging arm, whereby the weight of the arm and the attractive force of the magnet are caused to unite in retaining 65 the arm in an upright position.

3. The herein-described signaling-instrument, consisting of the upright swinging arm C, provided with an indicator or signal, and with the electro-magnet D, having the elongated core b, and the permanent magnet B, combined and arranged substantially as described.

WESLEY W. GARY.
